UNITED STATES PATENT OFFICE.

CHARLES E. REED, JR., OF OAK PARK, ILLINOIS.

COPYING LATHE.

Application filed November 30, 1927. Serial No. 236,666.

My invention relates, more particularly, to lathes provided for the manufacture of shoe lasts and more especially graded shoe lasts, of the type comprising, as an element, a 5 swing frame which, in lathes of this type as commonly provided, has revolvably mounted thereon the pattern and the work, to co-operate with a pattern follower and the cutter, respectively.

10 In the turning of irregularly shaped objects, as for example, and more particularly, some forms of shoe lasts it is necessary, in order that the machine operate relatively fast in the production of work of the 15 same shape as the pattern, where the pattern presents surfaces, as is common in some forms of shoe lasts, extending at a relatively small, acute angle to each other, to provide means to ensure the hugging of the follower by the 20 pattern at all times thereby to avoid rebound which results in inaccurate reproduction of the pattern.

My primary object is to provide means for the purpose stated which shall be of 25 simple and economical construction and by the use of which lathes for turning such objects may be operated at relatively great speed, thereby increasing the output of the machine.

30 While my improvements are applicable to quite a wide range of types of machines, I have chosen to illustrate them in a machine of the general type shown in the pending application of Charles E. Reed for U. S. patent 35 on lathes, Ser. No. 650,194, filed July 7, 1923, wherein the swing frame referred to is pivotally supported at its upper end and in the 40 operation of forming a last swings to one side only of the vertical plane in which the pivot for this frame is located.

Referring to the accompanying drawings: Figure 1 is a front view of a copying lathe embodying my improvements. Figure 2 is a view in end elevation of one end of the 45 machine. Figure 3 is a view in end elevation of the other end of the machine; and Figure 4, a broken view in longitudinal sectional elevation of a portion of the snubber mechanism for the swing frame.

50 Inasmuch as the machine shown is of the same general construction as that disclosed in the Reed application above referred to, except for the omission of certain parts and the addition of certain mechanisms to cause the machine to embody my present invention,

detailed showing and description of the machine appears to be unnecessary.

In explanation of the machine shown, it may be stated that the machine comprises a frame 5 equipped at one end with cutting 60 mechanism comprising a roughing cutter 6 and finishing cutters one only of which is shown at 7 which are rapidly rotated in the operation of the machine. At the other end of the frame is the usual pattern follower 8 65 arranged in spaced relation to the cutters in a direction lengthwise of the machine as shown. The machine also comprises a swing frame 9 which is pivotally supported at opposite ends thereof, at its upper edge portion, to the upper end of the frame 5, as represented generally at 10. This frame has rotatably mounted thereon rotatable head stock devices 11 and 12 which operate, through mechanism driven from the motor 70 represented at 13, a pattern last 14 and the work 15, the pattern 14 being supported by the head stock 11 and a stationary tail stock 16 and the work 15 by the head stock 12 and a stationary tail stock 17. In the operation of turning a last the rotating pattern 14 and rotating work 15 are forced against the pattern follower 8, and the cutters, respectively, the follower and cutting mechanism being fed to the left in Fig. 1 in a 85 direction lengthwise of the work and pattern.

In the particular arrangement shown force exerted by gravity upon the swing frame 9, tending to swing it to vertical position, 90 is augmented by a plurality of mechanisms represented generally at 18 and 19.

The mechanism 18 comprises a housing 20 mounted on a shaft 21 to float thereon, this shaft which continuously rotates during the 95 operation of the lathe and which may be operated in any suitable way, being shown as a shaft which is continuously operated by the motor 13 and through which power is transmitted to the mechanism for operating the carriages on which the cutters and pattern follower are mounted. The housing 20 which is peripherally enlarged, as represented at 22 to provide the annular space 23 between the housing and the shaft 21, is provided with a radially and upwardly extending arm 24 to the upper end of which the rear end of a rod 25 is pivotally connected as indicated at 26, the forward end of this rod being connected with the swing frame 105 110

at a point substantially midway between the ends of the latter, by a bracket 27 rigidly secured to a cross bar of the swing frame and pivotally connected, as represented at 5 28, to the forward end of the rod 25.

Located in the space 23 of the housing 20 and surrounding and rigidly connected with, the shaft 21, is a friction disk 29, the friction ring surface 30 of which flatwise opposes a 10 ring surface 31 in the housing 20, this surface being yieldingly pressed at all times against the friction ring 30, by a coil spring 32 located in a recess 33 in the housing 20 and bearing at its opposite ends against the end wall of 15 this recess and an end of a split collar 34 having threaded engagement with the shaft 21 to permit of its adjustment along the latter and relative to the housing 20 to vary the spring tension, ball bearings 35 and 36 being preferably interposed between the ends of the 20 spring 32 and the opposing portions of the structure. Thus under the continued rotation of the shaft 21 in counterclockwise direction in Fig. 3, the engagement of the friction disk 29 with the housing 20, as stated, 25 operates to exert a continuing force against the swing frame 9 tending to swing it to the left in Fig. 3, namely, in a direction toward the follower and cutting mechanism.

It is preferred that the mechanism just described be associated with other mechanism exerting force against the swing frame 9 tending to swing it in the same direction the 30 means shown for this purpose comprising 35 coil springs 37 one at each end of the machine. Each spring 37 is connected by an adjustable eye-bolt 38 with the lower end of the swing frame 9 and at its other end, by an eye-bar 39 with the upper end of an arm 40, two of these 40 arms being provided one at each end of the machine and rigidly connected with a rock-shaft 41. The arms 40 are linked to the swing frame 9, by links 42 pivotally connected at their rear ends, as represented at 43 to the up- 45 per ends of the arms 40 above the points at which the springs 37 connect with these arms, the other ends of the links 42 being pivotally connected, as indicated at 44, to the swing frame at points above those at which the 50 springs 37 are connected with this frame. The arms 40 and links 42, connected together by means of the shaft 41, form means for equalizing the movement of the swing frame 9 and preventing distortion thereof, and form 55 toggles at the ends of the swing frame which move toward extended position as the frame 9 swings outwardly and thus operate against the tension of the springs 37.

In the operation of the machine the pattern 60 and work are caused to bear with the desired pressure against the follower and cutting mechanism, by the action of the mechanisms 18 and 19, the mechanism 18 also serving to prevent rebound of the swing frame and ensure the hugging of the pattern by the fol-

lower at all times even when the lathe is operating at relatively high speed.

While it is preferred that the mechanism 18 be used in connection with other mechanism, such as the mechanism 19, I do not wish 70 to be understood as intending to limit my invention to its use with any other mechanism, as under certain conditions it may constitute the only means provided for swinging the frame 9 toward the follower and cutting mechanism in which situation it would serve not only as a pressure-producing device for the swing frame but also as a snubber to prevent rebound. Furthermore, while I have illustrated and described a particular embodiment of the combined pressure producing and snubbing mechanism for the swing frame, I do not wish to be understood as intending to limit my invention thereto, as the same may be variously modified and altered 80 without departing from the spirit of my invention.

What I claim as new, and desire to secure by Letters Patent, is:

1. A copying lathe, comprising, in combination, cutting mechanism and a pattern follower, a swing frame for the pattern and work, a rotatable member, means for rotating said member, and a spring-pressed device 90 frictionally driven by said member and operatively engaging said swing frame and operative to swing the latter toward said follower and cutting mechanism.

2. A copying lathe comprising, in combination, cutting mechanism and a pattern follower, a swing frame for the pattern and work, a rotatable member, means for rotating said member, friction disks, one of which is driven by said rotatable member, a spring yieldingly forcing the other of said disks into engagement with said first-referred-to disk, and means operatively engaging said spring-pressed disk with said swing frame, for the 100 purpose set forth.

3. A copying lathe comprising, in combination, cutting mechanism and a pattern follower, a swing frame for the pattern and work, a rotatable shaft, means for rotating said shaft, a housing member mounted on said shaft and relative to which the latter is rotatable, a friction disk secured to said shaft to rotate therewith in said housing, a spring yieldingly forcing said housing into frictional engagement with said disk, and means connected with said housing and operatively engaging said swing frame, for the purpose 110 set forth.

4. A copying lathe comprising, in combination, cutting mechanism and a pattern follower, a swing frame for the pattern and work, a rotatable member, means for rotating said member, a spring-pressed device frictionally driven by said member and operatively engaging said swing frame and operative to swing the latter toward said follower and 120 130

cutting mechanism, and other means exerting force on said swing frame tending to swing it toward said follower and cutting mechanism.

5. A copying lathe comprising, in combination, cutting mechanism and a pattern follower, a swing frame for the pattern and work, a rotatable member, means for rotating said member, a spring-pressed device fric-

tionally driven by said member and operatively engaging said swing frame and operative to swing the latter toward said follower and cutting mechanism, and other spring means exerting force on said swing frame tending to swing it toward said follower and cutting mechanism. ¹⁰ ¹⁵
